UNITED STATES PATENT OFFICE.

LOUIS EDWARD LEVY, OF PHILADELPHIA, PENNSYLVANIA.

MATRIX-MAKING MACHINE.

No. 827,872.

Specification of Letters Patent.

Patented Aug. 7, 1906.

Application filed April 7, 1905. Serial No. 264,264.

To all whom it may concern:

Be it known that I, LOUIS EDWARD LEVY, a citizen of the United States, and a resident of Philadelphia, in the county of Philadelphia and State of Pennsylvania, have invented certain new and useful Improvements in Matrix-Making Machines, such as are used in making stereotype printing-plates; and I do hereby declare the following to be a full, clear, and exact description thereof, such as will enable others skilled in the art to make and use my invention.

This invention relates to improvements in machines or apparatus which are adapted to be used in the production of papier-mâché stereotype molds, and in carrying out my invention a sheet is clamped between two separable parts of the apparatus to overlie a form of type and at the same time form the bottom of a hood or chamber into which air under compression is admitted, so that the matrix-sheet will be forced by air-pressure into the interstices of the type to produce a matrix from which a stereotype-plate can be made.

In the accompanying drawings, Figure 1 is a vertical section of a stereotyping-press embodying my improvements, and in such view I have shown a dry papier-mâché sheet placed immediately over the type and clamped between the sections of the machine; and Fig. 2 is a detail sectional view showing the application of a flexible air-tight diaphragm, a dry blanket under the same, and a moistened matrix-sheet over the type, the diaphragm being clamped between the sections.

The apparatus which I may use in carrying out my invention consists, preferably, of a stand A, upon which is supported a table B, having a depressed central portion which is adapted to support a form of type, and below such type-support there is a steam-chamber or other means for applying heat to the tabletop for the purpose of setting or drying the matrix-sheet. The table or top B has adjacent to its corners links D, which carry cam-levers E, the cam portion of said levers being adapted to engage the laterally-projecting rim of a hood or dome F.

The upper section of the apparatus comprises a hood or dome F, the lower part having a laterally-extending flange f and at suitable points handles f'. This dome is connected in any suitable manner with a coun-

terweight F', so that it may be raised vertically by said counterweight when the clamps are disconnected from the flange. A flexible pipe G enters the upper portion of the dome, such pipe being connected with an air-tank or pump, so that air under compression may be admitted to the dome and force the papier-mâché sheet against the type.

In forming a mold with a dry paper matrix a form of type H is placed so as to rest upon the centrally-depressed portion of the table. The matrix-sheet I is then placed over the type so that its edges will rest upon the plane upper surface of the table. The dome is now lowered so as to rest upon the marginal portion of the matrix-sheet and is clamped to the table by the cam-levers, so that said sheet forms an air-tight gasket between the sections of the apparatus. Air under compression is now let into the dome and forces the papier-mâché upon the type to form a matrix thereof. When a dry sheet of paper is used, it may be prepared so that the upper side will be air-tight. After the matrix has been formed steam may be let into the compartment C to heat the type and fix the dry matrix. After the dry matrix has been set the clamps are released and the dome raised, and when the sheet has been trimmed it is ready for the mold.

In Fig. 2 I have shown a manner of forming a matrix, using a moist sheet of papier-mâché, and when a moist paper sheet I is used it is overlaid by a dry blanket or other absorbent overlay K, above which is placed a sheet of rubber or other air-tight material L of sufficient size to extend beyond the form of type and be clamped between the table and the flanges of the dome.

By means of this apparatus I am enabled to employ a dome which is open at its lower end and make papier-mâché matrices either from moist or dry sheets, and the two sections of the apparatus are readily separable, so that the type and sheets may be readily placed in proper position.

I am aware that hydraulic pressure has been used in a press acting on a diaphragm to force the diaphragm against a matrix-sheet to form from type a stereotype-plate; but my apparatus overcomes the features objectionable to hydraulic pressure and is lighter, more cleanly, and there are no parts to get out-of order.

Having thus described my invention, what I claim as new, and desire to secure by Letters Patent, is—

1. In a matrix-forming press, a base having a plane margin and within such margin a depressed support for type, clamps maintained in movable engagement with the base, a hood having handles and a counterweight which is attached to the hood by suitably-guided flexible connections and a flexible pipe attached to the hood for admitting air under compression to the interior of the hood, the construction being such that a matrix-sheet may be clamped between the hood and base, said matrix-sheet overlying the type and forming the bottom of the hood to be forced by compressed air admitted into the hood against the type.
2. In a press for the purpose set forth, a

base having a depressed support for a form of type and a plane surface surrounding such depression, heating means below the type-support, a hood having a rim to overlie the margin of the base, a counterbalancing-weight flexibly connected to the hood and guided to exert an upward pull thereon, a flexible tube connected with the hood and with an air-tank for supplying air under compression to the hood and a sheet adapted to overlie the base and form of type supported thereby, such sheet forming the bottom of the hood, and means for clamping the margin of the sheet between the base and hood, for the purpose set forth.

LOUIS EDWARD LEVY.
